UNITED STATES PATENT OFFICE.

ELBERT B. SWERDFEGER, OF DENVER, COLORADO.

TONSILLOTOME.

1,291,244.

Specification of Letters Patent.

Patented Jan. 14, 1919.

Application filed November 24, 1917. Serial No. 203,816.

To all whom it may concern:

Be it known that I, ELBERT B. SWERDFEGER, a citizen of the United States, residing at Denver, in the county of Denver and 5 State of Colorado, have invented certain new and useful Improvements in Tonsillotomes; and I do hereby declare the following to be a full, clear, and exact description of the invention, such as will enable others 10 skilled in the art to which it appertains to make and use the same.

This invention relates to surgery and more particularly to an instrument for the removal of tonsils.

15 Difficulty has been encountered in the removal of tonsils by various types of instruments previously provided for this purpose because of the relative disposition of the operating devices and the snare-carrying 20 member, for the reason that the manipulating means and the carrying part of that portion of the instrument which is provided with the tonsil engaging member occupy a position which materially interferes with 25 the vision during the operation of the surgeon in the application and use of the tool upon a tonsil.

It is, therefore, one of the objects of the 30 present invention to so improve the construction of instruments of this type, that the vision of the operator is not interfered with during the application of the instrument.

It is a further object of the present invention to facilitate the adjustment of the snare over the tonsil and render the operation of 35 the device easier and more effective.

With these and other objects in view, as 40 will be rendered manifest in the following specification and apparent to those skilled in the art, the invention consists in the construction, combination, and in details of elements as more fully described hereinafter, one form of the instrument being illustrated 45 in the accompanying drawing, in which,

Figure 1 is a side elevation of the device with the snare loop adjusted in position to operate upon a left tonsil.

Fig. 2 is an end view looking toward the 50 snare loop in Fig. 1,

Fig. 3 is an underneath plan view of a portion of the instrument, showing the draw-rod and the rotatively or turnably adjustable casing section,

55 Fig. 4 is a cross sectional view of Fig. 1,

Fig. 5 is a cross section on line 5—5 of Fig. 1, and

Fig. 6 is a cross section on line 6—6 of Fig. 2.

An important feature of the present invention is the relative disposition of the snare-receiving loop to the carrying and operating parts of the instrument in such manner that the view of the operator or surgeon, in applying and operating the device 60 is not obstructed by the parts, and a further feature of the invention is the provision of means, whereby the snare-receiving loop may be readily adjusted on one or the other side of the axis of the operating means so 65 as to facilitate the adjustment of the snare-receiving loop over either the right or left tonsil without, in either case, interfering with the vision of the surgeon of the tonsil being operated upon. To the attainment of 70 these objects, I provide a tubular sectional casing or housing consisting of the parts A and B, the former of which is shown as rectangular in cross section and the latter as 75 circular in cross section, as clearly shown in 80 Figs. 4 and 5. The casing section B is provided, at its outer end, with a snare-receiving loop C which is disposed laterally as to the axis of the section B, and preferably is inclined rearwardly from the operating end 85 of the section so as to conform readily to the throat structure around the base of the tonsil when the casing A, B is inserted into the mouth of the patient. By this lateral and oblique disposition of the snare loop C, 90 a clear view along the side of the casing A, B is had by the surgeon, thus facilitating adjustment of the loop about the tonsil and rendering more effective the operation of the instrument when the snare, which is 95 usually in the form of a wire, (not shown), is withdrawn from the groove of the loop C, the groove being indicated at 2, in Fig. 6.

Extending through the section B of the casing is a so-called needle or rod member 100 3 having apertures 4 or other means, provided to receive the ends of the snare, the opposite end of the needle 3 being connected to a draw-rod or member 5 which may have a cross section conforming to the section of 105 casing A, the end of the rod projecting beyond the end of the section and being provided, in the present instance, with a knurled head or button 6 adapted to be engaged by one end of a lever 7 pivoted at the ears 8 110

of a companion lever 9, each of the levers being provided with a suitable handle portion, and the upper end of the lever 9 being pivoted or otherwise suitably connected as 5 at 10, to the adjacent end of the casing section A. In the position of the lever member shown in Fig. 1, the button 6 rests against the upper end of the lever 7 and the needle 3 is projected forwardly and exposed at the 10 end of the section B and is connected to the snare which is arranged in the loop C. Upon a closing movement of the handles of the levers, there is a relative movement of the needle or draw-bar in the casing A and 15 the casing B, so that the snare is withdrawn from its groove in the loop C, the contracting snare passing through and severing the tonsil.

To facilitate the use of the instrument 20 either upon right or left tonsils, the loop-carrying section C is adapted to be turned from one side to the other so as to appropriately dispose the loop C for right or left hand operation, and this is facilitated by 25 any suitable connection between the two casing sections A, B and as here shown, the sections may be provided with a sleeve 11 into which the ends of sections A and B may be inserted and the parts relatively secured in adjusted position by the set screw 12, or other suitable means.

Section B may be connected with section A in any suitable manner which will permit the revolving of one in relation to the other 35 so that in order to adjust section B so as to dispose loop C on one side or the other of the instrument it is only necessary to loosen the set screw and either withdraw section B from section A and reinsert it in the desired position or turn it as to section B to the desired position and then fix it in such position by setting the screw 11.

Preferably the loop C is braced to the section B by the provision of diagonal and 45 outwardly disposed braces 13, one of which is disposed on each side of the section B and secured to the outer side of the loop C so as to hold the latter firmly while it is being applied and also to prevent the 50 accidental breaking or fracturing of the loop

C at its connection to the end of the casing section B.

What is claimed is:

1. A tonsillotome comprising a sectional tubular casing, one of said sections being 55 angularly adjustable about the axis of the case and having a snare receiving loop bent angularly to, and attached at its side to, the said section, means for securing said sections in said relative angular positions, a 60 draw-rod extending through the casing and adapted for connection with a snare when arranged in said loop, and means whereby said rod and casing are relatively reciprocated.

2. A tonsillotome having a carrying member carrying a tonsil embracing lateral snare loop attached to and disposed wholly behind its front end, the plane of the loop inclined rear-wardly from the end of the carrying 70 member.

3. A tonsillotome having, in combination, a casing section and a tonsil embracing snare loop disposed obliquely to the axis of the casing section, which latter is connected at 75 its front end to one side of the loop, a line perpendicular to the plane and passing through the center of the loop transecting the axis of the section.

4. A tonsillotome having in combination 80 a casing section and a tonsil embracing snare loop disposed obliquely to and wholly rear-wardly of the front end of the section and means for securing the section to the instrument with the loop in either right or left 85 hand positions.

5. A tonsillotome comprising a tubular section having a snare loop at its front end, operating handles, and means for securing said section in any of various positions relative to the handles.

6. A tonsillotome comprising operating handles, a member carrying a snare loop, said member adapted to be reversed side for side as to the handles and means for securing the member to the said handles in either 95 of its positions.

In testimony whereof I affix my signature.

ELBERT B. SWERDFEGER.
